UNITED STATES PATENT OFFICE.

JOHN J. KELLY, OF NEWARK, NEW JERSEY.

DESIGN FOR HARNESS-TRIMMINGS.

SPECIFICATION forming part of Design No. 12,859, dated April 11, 1882.

Application filed January 10, 1882. Term of patent 7 years.

To all whom it may concern:

Be it known that I, JOHN J. KELLY, a resident of Newark, in the county of Essex and State of New Jersey, have invented and produced a certain new, useful, and original Design in Harness-Trimmings; and I do hereby declare the following to be a full, clear, and exact description of the invention, such as will enable others skilled in the art to which it applies to make and use the same, reference being had to the accompanying drawings, and to letters of reference marked thereon, which form a part of this specification.

Figures 1 and 2 are front and side elevations of a terret; Figs. 3, 4, and 5, views of check-hooks, and Fig. 6 a plan view of a buckle, all of which embody my design for harness-mountings.

The leading feature of this design consists in forming a flat mid-rib, *a*, upon the mountings, the said rib running longitudinally upon the outer or exposed face thereof, as shown in the several figures, and having upon each side of said mid-rib, and running parallel therewith, a concaved groove, *b*, the intersecting corners being approximately sharp. I spread an enamel within the said concaved groove, which, contrasting with the polished brass or other metal, is very effective.

I am aware that a mid-rib upon a harness-mounting is not new, as such is shown in the patent to Sargeant, No. 129,254, of 1872; but in this the concave groove on each side of the rib is not shown. There is also shown in the patent to Jones and Harris, No. 80,745, of 1868, a mid-rib, and on each side thereof a very slight concave; but all the corners are rounded, being as a whole of an ogee shape; and I therefore hereby disclaim anything shown in either of said patents.

What I claim is—

The design for harness-mountings, the same consisting in harness-mountings having a flat mid-rib upon the outer or exposed face thereof running longitudinally thereon, and having a depressed groove upon each side thereof, the intersecting corners being approximately sharp, as shown and described.

In testimony that I claim the foregoing I have hereunto set my hand this 4th day of January, 1882.

JOHN J. KELLY.
